UNITED STATES PATENT OFFICE.

JOSEPH BUCHHEIT, OF BROOKLYN, NEW YORK.

GAME.

SPECIFICATION forming part of Letters Patent No. 430,915, dated June 24, 1890.

Application filed September 9, 1889. Serial No. 323,361. (No model.)

To all whom it may concern:

Be it known that I, JOSEPH BUCHHEIT, a citizen of the United States, residing in Brooklyn, in the county of Kings and State of New York, have invented an Improved Game, of which the following is a specification.

My invention relates to a game played with blocks or "stones," somewhat after the manner of the game of dominos.

10 The invention will be plain from the following description and accompanying drawings, in which—

Figure 1 is a plan view showing the numbered blocks fitted into a holding frame or box; and Fig. 2, a like view showing some of the blocks colored differently from others, so as to present an ornamental design when the blocks have been fitted into place.

A represents the box for the blocks, and in 20 playing the game the blocks may be laid therein, if desired. I have in this instance shown seventy-two blocks, numbered from 1 to 72, inclusive. Half of them are shown rectangular and the remainder pentagonal.

25 In playing the game the blocks are placed upon the table, numbers down, and shuffled. Each player then takes a certain number of blocks, leaving some on the table or in the "pot." The player holding block No. 1 places 30 it in position, as in Fig. 1. Then the next player, if he has block No. 2, places it down; but if he has it not he must draw one block from the pot, and should he draw No. 2 he places it in position; but if he does not draw 35 2 he must pass. The next player then plays if he has block 2, and if not he must draw in same manner as first player, and so on. When

the pot is exhausted, the player not having the proper block to play must draw one, either from the player on his right or left, as may 40 be agreed. The winners of the game are those who first get rid of their blocks, and the final loser is the one who places the last or seventy-second block.

The blocks when laid present an ornamental design, as seen in Fig. 1. To enhance the effect of the design and produce other designs, the sides of the blocks may be colored differently.

It will be observed that each pentangular 50 block is equal to one square block and one-fourth of a square block, the one-fourth area of a square being the point formed by the two inclined sides. By thus shaping the blocks four of the pentangular blocks, when 55 placed together, form a symmetrical cross, as seen clearly in the drawings, the four pointed ends forming the central square.

I claim as my invention—

The combination, substantially as set forth, 60 of the rectangular blocks and the pentangular blocks, whose pointed ends form one-fourth the area of one of the square blocks, the pentangular blocks being differently colored from the square blocks, for the purpose described, 65 and all the blocks being consecutively numbered or marked to indicate the order in which they are to be played.

In testimony whereof I have hereunto subscribed my name.

JOSEPH BUCHHEIT.
